UNITED STATES PATENT OFFICE.

HANNIBAL BERRYMAN, OF CENTERVILLE, MONTANA.

ELECTRIC FIRE LIGHTER.

Application filed April 13, 1923. Serial No. 631,887.

To all whom it may concern:

Be it known that I, HANNIBAL BERRYMAN, a citizen of the United States, residing at Centerville, in the county of Silver Bow and 5 State of Montana, have invented a new and useful Electric Fire Lighter, of which the following is a specification.

This invention aims to provide a novel means whereby combustible material on the 10 grate of a stove or other heater may be ignited electrically, it being possible to adjust the electrode with respect to the grate bar so that a hot fat spark will be assured.

It is within the province of the disclosure 15 to improve generally and to enhance the utility of devices of that type to which the invention appertains.

With the above and other objects in view, which will appear as the description pro- 20 ceeds, the invention resides in the combination and arrangement of parts and in the details of construction hereinafter described and claimed, it being understood that, within the scope of what is claimed, changes in the 25 precise embodiment of the invention shown can be made without departing from the spirit of the invention.

In the accompanying drawings:—

Figure 1 shows in elevation, a device con- 25 structed in accordance with the invention, a portion of the frame work of the heater ap- 30 pearing in section; Figure 2 is a top plan wherein parts are broken away, a portion of the frame work of the heater appearing 35 in section.

The numeral 1 marks the frame of a stove 40 or other heater. The grate bars are design- 45 ated by the numeral 2 and are journaled at 3 for rocking movement in the frame 1. A tubular bearing 4 is secured in the 50 frame 1. In the bearing 4, a sleeve 5, pref- 55 erably made of insulating material, is mounted for longitudinal adjustment and for rotary adjustment. A clamping device 18, such as a screw is threaded into the bearing 4 and engages the sleeve 5 to hold the 60 sleeve in adjusted positions.

The numeral 6 denotes an electrode com- 65 prising arms 7 and 8 disposed at an acute 70 angle to each other. The angle in the elec- 75 trode 6, formed by the arms 7 and 8 is des- 80 ignated by the numeral 9. The arm 8 of the 85 electrode 6 extends through the sleeve 5. A 90 nut 10 is threaded on the arm 8 of the elec- 95 trode and serves to hold a conductor 11 on 100 the arm, in abutment with a washer 12 on

the arm, the washer bearing against the outer end of the sleeve 8. Not only does the nut 10 hold the conductor 11 on the arm 8, but, as well, the nut serves to move the 60 arm 8 of the electrode lengthwise until the angle 9 of the electrode is bound against the outer end of the sleeve 5. Thus, the elec- 65 trode and the sleeve are connected, for move- 70 ment together in one piece. The conductor 75 11 may form an end of the winding of a spark coil, and the other end of the winding of the spark coil is represented by a con- 80 ductor 14 connected to the frame 1 of the heater. In connection with the spark coil 85 and the device as shown in the drawings, an alarm clock may be used, so as to operate the structure at any predetermined time, thereby making it possible for a fire to be started without attention from an operator. 90

Because the arms 7 and 8 of the electrode 95 6 are disposed at an obtuse angle to each other, the arm 7 is given an inward inclina- 100 tion, and the upper end of the arm 7 lies relatively close to one corner of one of the 105 grate bars 2, as shown in Figure 2. When the set screw 18 is loosened, the sleeve 5 may be shifted endwise in the bearing 4, so as to adjust the distance between the upper end of the arm 7 of the electrode and the grate 110 bar 2, measured in the direction of the axis of rotation of the grate bar. It is desirable that, as shown in Figure 2, the upper end of the arm 7 of the electrode be disposed closer to one corner of one grate bar than to the 115 adjacent corner of the other grate bar, in order that the part may not spread and to 120 jump to both grate bars, thereby producing a spark of decreased efficiency. Since the sleeve 5 is mounted to rotate for adjustment 125 in the bearing 4, the upper end of the arm 7 of the electrode 6 may be swung in an arc, so as to bring the upper end of the said arm relatively close to one corner of one 130 grate bar, as depicted in Figure 2. When 135 the upper end of the arm 7 of the electrode 6 has been adjusted properly, the set screw 18 may be advanced so as to hold the sleeve 5, and consequently the electrode 6, in the 140 proper position.

145 What is claimed is:

In a device of the class described, a frame, a bearing mounted on the frame, a grate bar mounted on the frame, an electrode comprising angularly disposed arms, one arm terminating at a point adjacent to the grate 150 bar, a sleeve mounted in the bearing for

longitudinal adjustment and for rocking movement, the sleeve receiving the other arm of the electrode, means for holding said other arm of the electrode in the sleeve, and
5 a tightening device carried by the bearing and engaging the sleeve.

In testimony that I claim the foregoing

as my own, I have hereto affixed my signature in the presence of two witnesses.

HANNIBAL BERRYMAN.

Witnesses:

R. C. MACPHERSON,
D. R. WHITTINGTON.
